DENTAL MATRIX AND RETAINER
THEREFOR

Robert L. Sweeten, Salt Lake City, Utah

Application February 21, 1952, Serial No. 272,757

5 Claims. (Cl. 32—63)

1

This invention relates to a dental matrix and retainer therefor, and more specifically to a matrix retainer especially designed to facilitate the filling of cavities in the approximal, as well as the inner and outer sides of natural teeth.

One of the primary objects of this invention is to provide a matrix retainer of the type described with means for maintaining the matrix in position within the interproximal area between a pair of adjacent teeth.

A further object of this invention is to provide a unique and useful dental matrix retainer for retaining a filling material within a cavity while the restorative material is hardening or setting.

A still further object of this invention is to provide a dental matrix and retainer of simplified construction and which may be quickly and easily engaged and disengaged from the teeth while the matrix is in the mouth of the patient.

Another object of this invention is to provide a device of the type described which may be utilized in conjunction with the filling of cavities in either the upper or lower jaws.

Other and further objects and advantages of the present invention will become apparent from the following specification when read in light of the annexed drawings, in which:

Fig. 1 is an exploded perspective view of the matrix and retainer;

Fig. 2 is a side elevation, partly in section, showing the matrix and retainer positioned in the interproximal of a pair of adjacent teeth with the tension clamp applied to the anterior loop;

Fig. 3 is a longitudinal section taken on the line 3—3 of Fig. 1; and

Fig. 4 is an enlarged detail perspective view taken on the line 4—4 of Fig. 1, showing the connection of the threaded shaft with the bar.

Referring now more specifically to the drawings, reference numeral 2 indicates, in general, a matrix retainer clamp constructed according to this invention. The clamp 2 comprises an elongated, rectangular metallic base 4 of relatively thin transverse cross-section. One of the ends of base 4 is curved to form a socket 6 in which the cylindrical standard 8 is fixedly secured, as by welding. As seen in the drawings, standard 8 is of greater length than the width of base 4 and is positioned with its longitudinal axis substantially perpendicular to the longitudinal axis of base 4.

The other end of base 4 is bent laterally away from base 4 to form one arm 10 of a U-shaped bracket 12. The free end of arm 10 is reversely bent to form the other arm 14 of bracket 12.

2

A metallic bar 16, also having a relatively thin cross-section and of the same width as base 4, is held in sliding engagement with base 4 by clamp 18. One end of bar 16 is curved to form a socket 20 within which is secured, as by welding, one end of a second cylindrical standard 22. Standard 22 is of greater length than the width of the bar 16, and their respective longitudinal axes are perpendicular to each other.

The other end of bar 16 is deflected outwardly from base 4 and is crimped at 21 about the cone shaped end 23 of a threaded shaft 24. The other end of shaft 24 passes through aperture 26 formed in arm 10 and extends beyond the other arm 14 of bracket 12.

Shaft 24 is threaded through knurled nut 28 having a peripheral groove 30 which receives the free end of arm 14. As is now manifest, rotation of nut 28 will effect an adjustment of cylindrical standard 22 relative to standard 8 in a direction parallel to the longitudinal axis of base 4.

The matrix comprises an endless band 32, of thin, flexible, shim steel, which, under operative conditions, is removably mounted around standards 8 and 22.

Having now described in detail the component elements of the matrix and retainer, the operation thereof will be set forth with particular reference to Fig. 2.

Dental cavities are indicated by reference numerals 34 and 36 formed in an adjacent pair of anterior teeth 38 and 40, respectively, and it will be presumed that the dentist has prepared the teeth to receive a filling material formed of plastic or synthetic porcelain restoratives.

The filling material is then prepared and inserted in the cavities. Thereafter the matrix 32 is pinched together at 41 forming two loops 42 and 44 with loop 42 being approximately one third the size of loop 44. The matrix is then inserted between the interproximal area of the anterior teeth 38 and 40, with the loop 44 adjacent the anterior side of the teeth. A small piece 46 of hard but elastic material, such as gutta-percha is inserted within the smaller loop 42 positioned on the lingual side. Standards 8 and 22 are now inserted within loop 44 and nut 28 is rotated separating the standards from each other to tighten the band around the interproximal contour of the teeth, and to compress and retain the filling material in position in the cavities until it has set or hardened. Slippage through the interproximal area of the lingual loop 42 is prevented by the wedging action of element 46 in loop 42 on the lingual side of the teeth.

After the filling material has hardened, nut 28 is rotated to cause standard 22 to move toward standard 8 until they may be removed easily from loop 44, and the retainer 32 together with element 46 is removed from the interproximal area between the teeth.

The matrix and retainer may be sterilized easily since the parts thereof are easily assembled and disassembled, and are of non-complex construction.

Having set forth this invention in detail, it will be understood that the instant embodiment has been offered merely for the purpose of illustration and that the invention is only to be limited by the scope of the following claims.

I claim:

1. A dental matrix and retainer therefor comprising a thin endless band to be disposed in the interproximal area between a pair of adjacent teeth and forming a loop on the anterior and lingual sides of said teeth, a wedging element disposed within said lingual loop, and means for enlarging said anterior loop to tighten said loops around the interproximal contour of the teeth.

2. A dental matrix and retainer therefor comprising a thin endless band to be disposed in the interproximal area between a pair of adjacent teeth and forming a loop on the anterior and lingual sides thereof, a wedging element disposed within said lingual loop, and means for clamping said loops against the anterior and lingual sides of the teeth, said means comprising a base having a standard fixedly mounted thereon, a second standard mounted on said base, said standards being detachably positioned within said anterior loop, and means for moving said second standard relative to said first standard to exert tension on said anterior loop to clamp said loops against the anterior and lingual sides of said teeth.

3. A dental matrix and retainer therefor comprising a thin endless band to be disposed in the interproximal area between a pair of adjacent teeth and forming a loop on the anterior and lingual sides thereof, means for clamping said loops against the anterior and lingual sides of the teeth, said means comprising an elongated base having a standard at one end thereof, said standard extending transversely of said base, a bar slidably mounted on said base, a second standard affixed to said bar and extending transversely thereof, said second standard being substantially parallel to said first standard, said standards being positioned within said anterior loop, and means coacting with said base and bar for increasing the distance between said standards to exert tension on said anterior loop, whereby said anterior and lingual loops are drawn against their respective adjacent sides of said teeth.

4. A dental matrix and retainer therefor comprising a thin endless band to be disposed in the interproximal area between a pair of adjacent anterior teeth and forming a loop on the anterior and lingual sides thereof, means for clamping said loops against the anterior and lingual sides of said teeth, said means comprising an elongated

base having a standard at one end thereof, said standard extending transversely of said base and being of greater length than the width of said base, said base having a laterally extending arm provided with an opening therein, an elongated bar slidably mounted on said base, a second standard affixed to said bar at one end thereof and extending transversely thereof, said second standard being approximately parallel to said first standard and having a length greater than the width of said base and of said bar, said standards being detachably positioned within said anterior loop, a threaded shaft having one of its ends connected with the other end of said bar, the other end of said shaft extending through said opening formed in said arm, and a threaded nut mounted on the free end of said threaded shaft for moving said standards toward and away from each other to increase or decrease tension on said anterior loop.

5. A dental matrix and retainer therefor comprising a thin endless band to be disposed in the interproximal area between a pair of adjacent anterior teeth and forming a loop on the anterior and lingual sides thereof, means for clamping said loops adjacent the anterior and lingual sides of the teeth, said means comprising an elongated base having a standard at one end thereof, said standard extending transversely of said base and being of greater length than the width of said base, a laterally projecting arm on the other end of said base, said arm having an opening therein, the free end of said arm being reversely curved, a bar slidably mounted on said base, guide means securing said base and said bar in juxtaposed relationship, a second standard affixed to one end of said bar and extending transversely thereof, said second standard being parallel to said first standard and having a length greater than the width of said base and of said bar, said standards being detachably positioned within said anterior loop, a threaded shaft having one of its ends secured to the other end of said bar, the other end of said threaded shaft extending through said opening formed in said arm, a nut threaded on said threaded shaft at the free end thereof, said nut having a groove formed in its outer periphery intermediate the ends thereof, said reversely curved end engaging within said groove to engage opposed sides of said groove, whereby as said nut is turned in one direction or the other relative movement between said standards is obtained to increase or decrease the tension on said anterior loop.

ROBERT L. SWEETEN.
